CLAIM

The ornamental design for a sweeper broom, as shown and described.

DESCRIPTION

FIG. 1 is a perspective view of a sweeper broom showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof, shown with an attached handle, in which the handle is shown in broken lines.

FIG. 9 is an enlarged view of portion 9 of FIG. 2, outlined by the dash-dot-dot-line; and,

FIG. 10 is a cross-sectional view taken along the line 10-10 of FIG. 9.

The dash-dot-dot-lines shown in the drawings of the sweeper broom in FIG. 2 and FIG. 9 represent the boundaries of portion 9 and form no part of the claimed design. The broken lines shown in the drawings of a handle in FIG. 8 form no part of the claimed design.

The dash-dot-dot-dot lines illustrate the location from which the section drawings are created and shown in FIG. 10. The dash-dot-dot-dot lines form no part of the claimed design.
